Primary Examiner — Robin V Webster*Assistant Examiner* — Rachel A Voorhies(74) *Attorney, Agent, or Firm* — The Marbury Law Group, PLLC(57) **CLAIM**

The ornamental design for a display screen with graphical user interface, as shown and described.

DESCRIPTION

The sole FIGURE is a front view of the display screen with graphical user interface showing the design.

The broken line showing of a portion of the display screen in FIGURE is for the purpose of illustrating environment only and forms no part of the claimed design. The broken line regions within the graphical user interface and the areas within represent unclaimed portions of the design.

1 Claim, 1 Drawing Sheet(56)
